[57] CLAIM

The ornamental design for a brush organizer with brushes and detachable handle, substantially as shown and described.

DESCRIPTION

FIG. 1 is a perspective view of a brush organizer with brushes and detachable handle, showing my new design;

FIG. 2 is a top plan view;

FIG. 3 is a side elevational view taken in the direction of the brush to the left and to the rear in FIG. 1;

FIG. 4 is a side elevational view taken in the direction of the brush to the right and to the rear in FIG. 1; and

FIG. 5 is a bottom plan view.
